SEMI-AUTOMATIC SLIDER MOUNT FOR
ZIPPER ASSEMBLY
Moses Perlman, 4410 14th Ave., Brooklyn, N.Y.
Filed Feb. 14, 1961, Ser. No. 168,967
1 Claim. (Cl. 221—22)

The present invention relates to improvements in the art of assembling slide fastener parts so as to make zippers or slide fasteners, and more specifically, the invention relates to a new and improved device for the mounting of the sliding and coupling members, which usually are called "sliders" on the rows of interdigitating elements of a slide fastener, so as to complete slide fasteners or zipper units.

The attaching of sliders to zipper units, when done by hand requires a certain amount of skill in order to complete any appreciable quantity of zippers during a certain period of time; however, even skilled operators are not able to attach manually more than six thousand sliders to six thousand zipper units per day. The best mechanical devices hitherto developed have used a mechanism, actuated by solenoids and micro switches. Such a mechanism is too expensive and too complicated for being used widely in the highly competitive business of making slide fasteners.

Therefore, one object of the present invention is the provision of a device of the character described which simplifies and facilitates the mounting of sliders on zippers to such an extent that an unskilled worker can attach in a perfect manner twelve thousand to thirteen thousand sliders to zippers during an ordinary eight-hour day.

Another object of the present invention is the provision of a device of the character described which is simple and inexpensive in construction since it consists of only a few parts that can be manufactured and assembled by mass production processes, and which does not require any electrical parts such as solenoids or micro switches or the like.

A further object of the present invention is the provision of a device of the character described which is comparatively small in size, and light in weight, so that it can be installed easily or mounted on a table or the like at locations which are most convenient in relation to other pieces of machinery used during the zipper making process.

With the foregoing and other objects which will appear as the description proceeds, the invention consists of certain novel details of construction and combinations of parts hereinafter more fully described and pointed out in the claim, it being understood that changes may be made in the construction and arrangements of parts of the embodiment disclosed without departing from the spirit of the invention as claimed.

In the accompanying drawing I have set forth an illustrative embodiment of my invention.

In said drawing:

FIGURE 1 is a top plan view of a preferred embodiment of my invention with a fraction of its top cover shown open so as to present a fractional top view of the inner mechanism;

FIG. 2 is a side elevation;

FIG. 3 is a detailed side elevation of the interior mechanical elements of a modification; and,

FIG. 4 is a fractional top view of the modified elements of FIG. 3.

Similar reference characters refer to similar parts throughout the several views.

In the drawing the numeral 1 denotes a casing having a top portion 2, and wall portions 3, as well as a

2

base portion 4 (FIG. 2). Attached to a wall portion 3 of the casing 1 is a channel member 5 which has a V-shaped end portion 7 and a longitudinal channel 10 as well as a traverse channel 11 that crosses the channel 10, as may be seen in FIG. 1. The member 5 also has a recessed portion 12 of a substantially inverted U-shaped formation, and in which are rotatably arranged a pair of disks 15, which have bevelled, reduced end portions and are mounted on a shaft 17 that is rotatably mounted in bearings 20. The bearings 20 are mounted on the casing 1, through a portion of which the shaft 17 is traversely extended. A pair of ring members 21 and 22 are firmly secured to the shaft 17, and a friction disk 23 is secured to the member 21. A sprocket wheel 24 is rotatably and shiftably mounted on the shaft 17, and is connected by means of a sprocket chain 25 to a small sprocket pinion 27, that is secured to a shaft 30 of a reduction gear 31, which is in driving engagement with an electric motor 32 mounted within the casing 1. A counter friction disk 33 or any other suitable surface preferably is secured to the wheel 24, and is in engagement with the friction disk 23, and a pressure spring 34 is interposed between the member 22 and the wheel 24, so that the member 21 and the shaft 17 will be taken along and caused to rotate if the wheel 24 is being rotated, provided there is no considerable force exerting a braking action on shaft 17, in which case a slipping of the elements 23 and 33 on each other will be caused, allowing a rotation of the wheel 24 without tacking along the parts 23, 21, 17 and 15.

One, or two, or more cross pins 35 are traversely extended from one of the disks 15 to the other and are secured thereto. A knob 37 is secured to that portion of the shaft 17 which extends through the channel member 5 and beyond the same.

A slide arrester 40, which may be of any suitable shape and construction, is mounted on the top wall portion 2 of the casing 1. In the instance shown the arrester 40 consists of a base 41 carrying a bi-furcated upright member 42, to which is pivotally attached at 43, a curved lever 44. A downwardly extending oblique end portion 45 of the lever 44 is forced by a spring 49 to extend into the way of a row of sliders 47, which are being slid down by means of gravity, from a slider handling device (not shown), on a guide rail 50 toward the intersection of the channels 10 and 11 of the member 18.

If the members 15 and 17 are rotating in a counter-clockwise direction, any slider 47, extending into the channel 10 and arrested in its sliding movement by the arrester 40, will be engaged by one of the pins 35 and will be moved away from the arrester 40, toward the end of the channel 10; there the thus engaged slider 47 will be stopped, and with it will also be stopped any further rotation of the parts 15 and 17, while the elements 23 and 33 are in frictional relationship to one another. The said stopped slider is now in a convenient position for being inserted by an operator in between the rows of interdigitating elements of a slide fastener or zipper unit. Thereby the said slider is removed from the device, so that the aforementioned braking action ceases, and another slider is being pushed into the place of the aforementioned slider 47 by the action of the elements 35, 15 and 17 in the above described manner.

According to the modification of FIGS. 3 and 4, the elements 15, 17, 21 and 24 are replaced by a pair of wheels 51 mounted on a shaft 53, and connected by a pair of chains 54, or a belt or the like, to another pair of wheels 55, which are rotatable on a shaft 57. Here, the wheels 51 are firmly secured to the shaft 53, as are the disks 15 in the embodiment of FIGS. 1 and 2, and

the chains or the like 54 are connected to each other by traverse pins 60 which are adapted for engaging sliders in the same manner as the pins 35 of FIGS. 1 and 2. Rotatably and shiftably to the shaft 53 is attached a wheel 61, which is driven by a belt 62 or the like, that passes round a pulley 63 of a reduction gear 64, driven by a motor 66. The wheel 61 also is provided with a friction surface 67, that is in frictional engagement with a friction disk 70 attached to a ring member 71 which is firmly secured to the shaft 53.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention which as a matter of language might be said to fall therebetween.

Having thus fully described my said invention, what I claim as new and desire to secure by Letters Patent is:

A slider mount for zipper assembly comprising a channel member having a V-shaped end portion and a longitudinal channel portion adapted for a slider to be moved therethrough and a cross channel portion right-angularly disposed to and extended through said longitudinal channel portion and having also a recessed portion of an inverted U-shaped formation the upper web section of which is semi-circular and has an upper section that extends into the longitudinal channel portion of said channel member at the crossing of the longitudinal channel portion with the cross channel portion, a pair of disks in spaced relation to each other being rotatably mounted

in the recessed portion of said channel member and having bevelled opposite peripheral portions extending into that section of the channel member at which the cross channel portion crosses the longitudinal channel portion, pins adapted for engaging sliders connecting peripheral sections of said disks to each other, a casing having top portions and vertical wall portions to one of which said channel member is attached, a shaft to which said disks are secured being rotatably extended through opposite wall portions of said casing, ring members in spaced relation to each other being secured to said shaft, a wheel rotatably and shiftably mounted on said shaft intermediate said ring members, resilient means interposed between a first one of said ring members and said wheel, tending to press said wheel against a second one of said ring members for frictional engagement therewith, driving means for rotating said wheel, a horizontal lever (44) pivoted to the top portion of said casing having a downwardly curved end portion juxtaposed to the intersection of said longitudinal channel portion with said cross channel portion, and resilient means tending to keep said lever in a position in which it is disposed at an acute angle to said longitudinal channel portion and in which the oblique end portion of the lever is above said longitudinal channel portion, said lever being adapted for temporarily arresting the movement of each slider until engaged by one of said pins.
